Patented Sept. 21, 1915.

UNITED STATES PATENT OFFICE.

FRANK KUHN, OF DETROIT, MICHIGAN.

ELECTRICALLY-HEATED OVEN.

1,154,416.

Specification of Letters Patent. Patented Sept. 21, 1915.

Application filed October 31, 1914. Serial No. 869,551.

To all whom it may concern:

Be it known that I, FRANK KUHN, a citizen of the United States of America, residing at Detroit, in the county of Wayne and State of Michigan, have invented certain new and useful Improvements in Electrically-Heated Ovens, of which the following is a specification, reference being had therein to the accompanying drawings.

10 The invention relates to electrically-heated ovens and comprises the novel construction and arrangement of parts as hereinafter set forth.

In the drawings: Figure 1 is a perspective view of the oven with the shield removed; Fig. 2 is a transverse section; Fig. 3 is a plan view of the heating unit; Fig. 4 is a sectional view partly in plan of the heating unit support.

20 It is the object of the invention to obtain a construction which is both inexpensive to manufacture and is efficient in its operation. To this end the oven is formed of an outer sheet metal casing A and an inner casing B 25 of rectangular form, spaced from each other and provided with suitable heat insulation C therebetween. The heating unit D is preferably formed by a naked coiled resistor E which is strung through insulator spools or 30 knobs F supported on a frame G. The frame comprises merely straight bars of metal, which are spot-welded to each other at the points of crossing, their projecting ends G' abutting against the walls of the 35 oven and holding the resistor out of contact therewith. The frame is removably supported above the oven bottom by engaging the ends of the cross-bars with a grooved guide H, preferably of channel section. The 40 insulator spools may be suspended from the frame by metallic clips I centrally spot-welded to the bars G and bent around the grooves in the spools. The terminal contacts J for the resistor are mounted upon an insulator block K and are arranged to engage stationary contacts L in an insulator block M mounted when the unit is in place.

The heating unit when in operation will dissipate its heat both by radiation and 50 convection. The fact that the resistor is arranged around the margin of the frame will prevent overheating at the center of

the oven and will cause the convection currents of heated air to pass upward along the side walls of the oven. To prevent interference with the ascending air currents, the shelves or gratings in the oven are spaced from the side walls thereof and are supported by guides N, preferably of channel section, secured to a vertical bar O preferably by spot-welding. This bar O may also form 55 a securing means for the channel guide H, by which the unit frame is supported and the bars themselves may be secured either by bolting or by spot-welding or other suitable means to the walls of the oven. The shield P is placed over the frame G to protect the resistor, and the marginal portion of this frame is perforated, as at Q, for the 60 passage of the convection currents. There 65 is also a downturned flange R at the forward edge of the shield which protects the resistors when the oven door is open.

In use, the food to be cooked may be supported either upon the shield P or, preferably, upon shelves or gratings S which may be adjusted to different heights by engagement with the guides O. Where several shelves are used the hot air will find access 70 to the spaces therebetween by first passing 75 upward through the clear space between the oven wall and the guides O and then passing laterally inward.

What I claim as my invention is:—

1. An electrically heated oven, comprising 85 a casing, a frame formed of cross-bars fitting within the oven in a plane parallel to the bottom thereof, said cross-bars having projecting ends abutting against the walls of the casing, and a naked resistor extending 90 around the margin of the frame substantially adjacent to said cross-bars and carried thereby.

2. An electrically heated oven comprising 95 an oven casing having a door, a frame supported within said casing, a heating unit supported by said frame, and a shield upon said frame having a down-turned flange normally adjacent the door for protecting the heating unit.

3. An electrically heated oven, comprising 100 a casing, a frame slidably detachably suspended within said casing and provided with insulator supports, a naked resistor sus-

pended from said insulator supports in a plane parallel to the bottom of the casing, terminal contacts for said naked resistor, and stationary contacts carried by said casing, said terminal and stationary contacts being adapted to engage each other when the unit is in place.

In testimony whereof I affix my signature in presence of two witnesses.

FRANK KUHN.

Witnesses:

C. H. REUTELSTERZ,
ROLAND DRESSEL.
